UNITED STATES PATENT OFFICE.

FRANK J. W. WEISER, OF ELMHURST, ILLINOIS.

PIANO.

1,275,806.

Specification of Letters Patent. Patented Aug. 13, 1918.

Application filed June 21, 1916. Serial No. 104,880.

To all whom it may concern:

Be it known that I, FRANK J. W. WEISER, a citizen of the United States, residing at Elmhurst, in the county of DuPage and

5 State of Illinois, have invented certain new and useful Improvements in Pianos, of which the following is a specification, reference being had therein to the accompanying drawing.

10 My invention relates to pianos, and its object is to provide a new and useful organization of parts whereby the alinement of the fall-board in its backward and forward movements is preserved so that its ends will 15 not strike or bind on the side-arms of the case, and the top-frame or music desk may be swung automatically to inclined position when the fall-board is moved inwardly.

In the accompanying drawings which 20 illustrate an exemplification of my invention in its practical and preferred embodiment,

Figure 1 is a front view of the upper portion of an upright piano provided with my invention, part of the top-frame being 25 broken away for convenience of illustration;

Fig. 2 is a vertical sectional view with the parts in their positions when the fall-board is closed, and

30 Fig. 3 is a similar view with the parts in their positions when the fall-board is opened and moved back to expose the keys for playing.

In the drawings, the reference numeral A 35 indicates an upright body of any suitable and conventional form having the usual keys a , key-bottom a' , key-slip a'' , side-arms a^3 , and the necessary strings, hammers and accessories (not shown). The body is pro-

40 vided with a top-frame or music desk B, which is pivoted at or near its top as at b to the body so that its lower edge which is provided with a music-shelf b' may be swung outwardly or forwardly to place the 45 frame in inclined position.

The fall-board C preferably is made in front and rear sections c and c' , respectively, which are connected by hinges c^2 so that the front section may be folded or turned

50 back on the rear section, and the rear section rolls or slides on guides c^3 on the side arms.

A pair of levers D are provided, one at each end of the top-frame or music desk, and 55 which in the form shown constitute kickers adapted to swing the desk or frame out-

wardly on its hinges when the fall-board is moved rearwardly and to allow the frame or desk to swing inwardly to its vertical or out-of-use position when the fall-board is closed. These kickers may be of any suitable form or construction and may be suitably mounted in the path of the fall-board and operated thereby to swing the desk or top-frame, but preferably I make them in

60 the form of curved extensions of the levers D forming the pivoted end-arms of a frame mounted in the rear of the fall-board and top-frame or desk and comprising the upper cross-guide D', which is rigidly sup-

65 ported at its ends on the side-arms a^3 and to which the levers are pivoted or hinged as at d , and the lower cross-brace D² which connects the lower ends of the levers. The rear of the fall-board is hinged or pivoted

70 to the lower ends of the levers as at d' , and the upper ends of the levers forming the kickers are extended above the piece D' and forwardly curved to bear against and move the part B which may be provided with

75 wear-plates b^2 for the kickers. By this construction the levers and the upper and lower cross-pieces D' and D² form a unitary frame which may be made outside the piano case and assembled in the case as a unit by

80 merely fastening the cross-guide to the side-arms. The levers are pivoted on the cross-guide D' so as to swing only backward and forward without any lateral motion, and the synchronizing cross-brace D² extends across

85 the piano and is rigidly connected at its ends to the levers below their fulcrums, so that the levers and cross-brace form a swinging frame which moves back and forth uniformly and evenly at all points in its length

90 when force is applied to it with consequent uniform motion of the levers, and as the fall-board is hinged directly to the lower ends of the levers it is thereby positively and rigidly held against lateral displacement

95 and moves evenly and uniformly at both ends irrespective of the point where force is applied to it so that its alinement in

100 its backward and forward movements is preserved and its ends will not strike or

105 bind on the side-arms.

The kickers are preferably mounted at the ends of the piano when the top-frame is adapted to be swung to be used as the music desk, but they may be disposed at any suitable points as for example when only part of the top-frame is swung for that purpose.

The sectional fall-board is preferably used on small pianos as it occupies less space than the ordinary fall-board.

When the fall-board is in its forward or projected position the kickers exert no pressure on the desk so that the latter may swing down into its closed position, but when the fall-board is moved to its inner or retracted position it causes the kickers to bear upon the desk and swing it to its open position, the return of the fall-board to its forward position allowing the desk to resume its closed position.

I claim:

1. In a device of the class described, the combination of a piano music-desk, a fall-board horizontally movable into projected and retracted positions below the desk, levers pivotally mounted in the piano and having their lower ends adjacent the rear of the fall-board, a synchronizing cross-piece rigidly connected to the levers below their pivots to move the levers in unison to preserve the alinement of the fall-board in its

movements, and hinges connecting the fall-board and lower ends of the levers.

2. In a device of the class described, the combination of a piano music-desk pivotally mounted to swing outwardly, a fall-board horizontally movable into projected and retracted positions below the desk, a cross-guide mounted in the piano above the fall-board, levers pivoted on the cross-guide and having their upper ends forwardly curved to bear on the music-desk, hinged connections between the lower ends of the levers and the fall-board, and a synchronizing cross-brace rigidly connecting the lower ends of the levers below their pivots to move the levers in unison to preserve the alinement of the fall-board in its movements.

In testimony whereof I affix my signature in presence of two witnesses.

FRANK J. W. WEISER.

Witnesses:

J. McROBERTS,
EDITH WILCOX.
